J. A. COCHRAN

AWNING FIXTURE

Filed June 20, 1921

Fig. 5.

INVENTOR.

John A. Cochran.

John A. Cochran
ATTORNEY.

UNITED STATES PATENT OFFICE.

JOHN A. COCHRAN, OF PASADENA, CALIFORNIA, ASSIGNOR TO ANDREW SWANFIELDT, OF LOS ANGELES, CALIFORNIA.

AWNNG FIXTURE.

*Application filed June 20, 1921. Serial No. 479,166.

To all whom it may concern:

Be it known that I, JOHN A. COCHRAN, a citizen of the United States, and a resident of Pasadena, in the county of Los Angeles 5 and State of California, have invented new and useful Improvements in Awning Fixtures, of which the following is a specification.

This invention relates to awning fixtures 10 and has for its principal object to provide a fixture whereby awnings and the like which are disposed exteriorly of a building or room may be readily operated from the interior thereof.

15 It will be understood in the consideration of this invention that awnings of the above type commonly known as "inside, outside awnings" are provided with a pole at the lower end thereof having its ends projecting 20 from each side of the awning. A pair of cords are used for operating the awning, a cord being disposed adjacent each side thereof. Each cord is fixed at one end to the wall 25 of the building or other surface adjacent the upper end of the awning, and is passed downward over the protruding end of the pole and thence upward.

An opening is provided in the wall in alignment with one of the cords, which cord 30 passes through this opening to the other side of the wall or to the interior of the building or room. The other cord passing over the remote end of the pole is carried vertically upward along the side of the awning and 35 passes over a pulley fixed to the wall, adjacent that side of the awning. This cord is passed from the pulley horizontally across, adjacent the upper end of the awning, to the opening provided in the wall. Thus, the 40 operated end of both cords passes through the same opening and the awning is raised or lowered, as desired, by means of the cords which are operated jointly.

It is found in practice however that the 45 cords do not operate readily, inasmuch as they tend to draw unevenly and wear rapidly on being drawn over rough surfaces, such as the margins in the opening at the wall. It is therefore an object of my invention to provide a fixture adapted to be placed over or 50 adjacent the usual opening, provided in the wall, the fixture being adapted to guide the cords to facilitate smooth operation and to prevent abrasion thereof.

55 To this end I have provided, and will here-

inafter describe, a fixture of the above character which embodies two sheaves rotatably mounted therein, one sheave having its axis of rotation disposed at right angles to the axis of rotation of the other sheave.

60 I have illustrated my invention in the accompanying drawings, in which:

Fig. 1 is a plan view of one embodiment of the invention.

Fig. 2 is a view in section, as seen on line 65 2-2 of Fig. 1.

Fig. 3 is a view in front elevation of an awning of the vertical or drop type, illustrating the application of my invention thereto.

Fig. 4 is a view in vertical section, as seen on line 4-4 of Fig. 3.

Fig. 5 is a view in end elevation of another type of awning, showing the application of 70 the fixture to that type.

In carrying out my invention, I employ the fixture 6 shown particularly in Figs. 1 and 2, which in the embodiment shown, comprises two brackets 7 and 8, which jointly hold a pair of sheaves 9 and 10 rotatably mounted upon and supported thereby on a common plane. The sheaves are disposed so that the center of rotation of one is at right angles to the center of rotation of the other. The brackets may be of any suitable construction for the purpose of rotatably holding the sheaves, but in the preferred embodiment of the invention, as illustrated, the brackets are formed with a vertical wall 11 80 bent at right angles as indicated at 12, the bracket 8 being therefore shorter than the bracket 7, so that corresponding ends 13, 13 and 14, 14 are parallel. The bracket 7 is provided with a base portion 15 extending at an angle of 45 degrees with respect to the 85 major axis of each wall, and is formed with rounded ends 16, to present a neat appearance. Each end of the base portion is provided with openings 17 for receiving screws 18 to hold the fixture securely in position upon the wall or other surface.

It will be observed that the base portion and the walls are formed integrally from a blank of sheet metal, and the construction although extremely simple is rigid. The bracket member 10 is provided with a triangular web 19 formed integrally with the vertical wall of the member which is also formed from a single piece of metal to permit of economical manufacture while providing extreme rigid- 90 95 100 105 110

ity. Each sheave is provided with a pin 20, passing loosely therethrough, upon which the sheaves rotate. The pins serve also to join bracket 9 to the bracket 10 to form a unit fixture. For this purpose an end 21 of the pin is formed with a rounded head of enlarged diameter, and the other end 22 is peened over, after the manner of a rivet to hold the two members in fixed spaced relation to each other, a shoulder 23 being provided on this pin adjacent each end and abutting the inner surfaces of the members 9 and 10.

Referring now particularly to Figs. 3 and 4, 25 indicates an awning of the vertical type; shown in its fully lowered position; for the purpose of closing a window 26 or a similar aperture in a building. The awning is secured at its upper end 27 to a casement 28 by means of hooks and eye-bolts 29 and 30 respectively. After the manner common to these awnings, a pole 31 is provided at the lower end thereof having its ends 32 and 33 respectively, protruding beyond the adjacent sides thereof. The awning is adapted to be raised and lowered by means of two cords 34 and 35 respectively, each of which are fixed at their upper ends, as at 36, to the casement at a point somewhat above the top of the awning. At a position above the awning and immediately to one side thereof, is located the fixture 6 which is secured to the casement as explained, and disposed so that the space 37 between the two members of the fixture is disposed in alignment with an opening 38 provided in the casement. The fixture is so disposed that one sheave has its axis of rotation on a vertical plane. The cord 34 passes downwardly from the point at which it is secured to the casement and over the protruding end of the pole and thence upward over the sheave 10 through the space 37 and the opening 38. The cord 35 is similarly arranged over the other end of the pole and passes vertically upward parallel with the adjacent side of the awning to a pulley 39 which is fixed to the casement in alignment with the cord, and over which the cord passes so as to extend horizontally across the casement above the awning to the other sheave of the fixture. This cord likewise passes through the space 37 and the opening 38. This arrangement results in the ends of each cord being convenient for operation within the interior of a building or any point behind the wall.

To raise the awning from the position shown, both cords are drawn inwardly over their respective sheaves which rotate freely and definitely guide these cords. By virtue of the frictional contact of the cords with the respective ends of the pole, the pole will be caused to rotate as the cords are drawn inwardly to decrease the distance between the looped end thereof, and the fixed end of

the awning. As the pole is thus rotated, the awning is wound around it as the pole rises, in the manner well known and common to these types of awnings.

It will be observed that the sheaves hold the cords passing thereover spaced from contact with any surface and further hold them definitely in alignment relative to the respective ends of the pole, as well as holding the cord aligned relative to the pulley, so that the usual uneven operation or abrasion of the cord is obviated.

Referring now to Fig. 5, the invention is shown as applied to an awning 40 of the sloping type, in which a pole 41, having its ends 42 protruding through the awning ride upon and are supported by a tubular frame structure 43, common to these types of awnings, which is fixed to an outer wall of a building 44. The awning is operated in a manner similar to the one above described, and is for this purpose provided with two operating cords, 45, and 46, each having an end fixed to the building as at 48. In the structure shown the fixture 6 is mounted in a manner substantially the same as shown in Fig. 5 and the cords pass through an opening 49 provided in the wall 50 of the building 51 to the interior thereof. The awning is raised or lowered by operating the cords in the manner described. The frictional contact of the cords with the end of the pole causing the pole to rotate and wind the awning thereon as it is drawn upwardly upon the frame.

It is apparent that I may modify the arrangement and structure of my invention within the appended claims without departing from the spirit of my invention or enlarging the scope thereof.

What I claim is:

1. An awning fixture comprising a bracket formed of two members having base portions in the same plane, for attachment to a wall or the like, and correspondingly formed right angular vertical portions uniformly spaced apart, a pair of sheaves mounted between said vertical portions, and having their axis disposed at right angles and in the same plane, said sheaves being held between the parallel vertical portions of said bracket members for receiving and confining cords adapted to be extended over said pulleys in the space of said bracket.

2. An awning fixture comprising a bracket formed of two members having base portions in the same plane for attachment to a wall or the like, and correspondingly right angularly formed vertical portions uniformly spaced apart, a pair of sheaves mounted between said vertical portions and having their axis disposed at right angles and in the same plane, said sheaves being held between the parallel vertical portions of said bracket members for receiving and

confining cords adapted to be extended over said pulleys in the space of said bracket, and pins rigidly connecting the parallel vertical portions of said bracket members 5 and forming bearings for said sheaves.

3. An awning fixture including a bracket member having right angularly disposed portions, webs extending outwardly from said portions for attachment to a wall or 10 the like, a secondary bracket member also having right angularly formed portions paralleling the right angular portions on

said first member, and spaced therefrom, and provided with a web portion for attachment to the wall pins, spanning the 15 spaces between and rigidly connecting the parallel portions of said bracket members, and sheaves rotatably held on said pins and between said bracket members, as described.

JOHN A. COCHRAN.
